LINING AND TIE

Max Kleinmann, New York, N. Y.

Application March 23, 1937, Serial No. 132,461

3 Claims. (Cl. 2—146)

This invention relates to cravats or neckties in which a long and narrow strip of fabric is entered between the folds of a collar and held by a knot at the front, the invention being an improvement on my co-pending application, filed November 18, 1936, Serial Number 113,389.

An object of this invention is to provide a four-in-hand tie with a longitudinally creased reinforcement whereby the central longitudinal outer portion of the tie is shaped to produce a ridged appearance on its outer side as demanded by fashion.

A further feature is in the provision of means by which the lining re-enforcement of the tie is secured and prevented from lateral movement.

Another aim is to produce means by which patterns of the fabric may be held in matched relation.

These objects are attained by the novel and practical construction and combination of parts hereinafter described and shown in the accompanying drawing forming an essential part of this disclosure, and in which:

Figure 1 is a plan view of a conventional tie extended at full length.

Figure 2 is a perspective view of the tie showing the first operation of adjusting.

Figure 3 is a similar view of the tie after the knot has been formed.

Figure 4 is a plan view of the lower part of the tie, parts being broken away to show the arrangements of parts.

Figure 5 is a side view of the parts seen in Fig. 4.

Figure 6 is a transverse sectional view taken on line 6—6 of Fig. 5, the folded crease being accentuated.

Figure 7 is a fragmentary front elevational view of a tie knotted ready for use.

Figure 8 is a cross sectional view taken on line 8—8 of Fig. 7.

Referring in greater detail to the drawing, the usual long strip tie, designated generally by the numeral 15 is formed with a main outer portion 16 or wing 16 and a minor end portion 17, the central part being parallel in width.

A lining 18 is arranged within the wing 16 and, in the present disclosure, is split longitudinally at the center, as at 19, or if the lining material is quite flexible, it may be folded only.

A sheet of strong, fairly stiff fabric 20 is folded

along its longitudinal center, as in Figure 6, and is secured by an adhesive 21 to each side portion of the folded lining to maintain it in the preferred position, see Figs. 5, 6 and 8, the effect being to cause the wing 16 to crease along the center of its width, giving a desirable appearance to the tie after the knot has been made.

The smaller end 17 of the tie is passed through a loop 22 on the underside of the wing 16, centrally thereof, thereby retaining the parts in proper adjustment and aiding in tying the knot 23.

As shown in Figs. 1, 2 and 3, the tie material is of a single color having a single transverse bar or band 25 and an L shaped device 26, of different color which upon forming the knot exactly joins the bar 25, increasing the comely appearance of the completed knot and giving positive assurance that it has been properly tied.

Due to the simplicity of adjusting the tie it can be applied in the dark, or by blind persons or children.

No one should be able to improve the lining for the purpose of the crease.

Having thus described the invention and set forth the manner of its construction and use, what is claimed as new and sought to secure by Letters Patent, is:

1. A necktie having a lining folded lengthwise at the center below the knot, and a stiff fabric reinforcement shaped to present angularly disposed side portions and secured in the lining, said reinforcement and lining operating to produce a longitudinal crease in the tie front. 30

2. A necktie having a lining within its main portion, said lining being slit longitudinally at its center below the knot, a firm fabric reinforcement bent lengthwise centrally of its width to produce angularly disposed side portions and held by an adhesive to said lining over the slit, and means for guiding the minor portion of the tie when making the knot. 35

3. A necktie having a lining within its main portion, said lining being slit longitudinally at its center below the knot, and a firmly adherent fabric reinforcement covering the lining adjacent the slit, said reinforcement folded longitudinally centrally of its width to produce equal side portions disposed at an angle to each other. 45

MAX KLEINMANN.
